UNITED STATES PATENT OFFICE.

GUSTAVE A. PIEPENBRING, OF STRATFORD, CONNECTICUT, ASSIGNOR TO THE AMERICAN FABRICS COMPANY, OF BRIDGEPORT, CONNECTICUT, A CORPORATION OF CONNECTICUT.

AUXILIARY THREAD EXTRACTOR.

Application filed July 28, 1925, Serial No. 46,586.

This invention relates to a device for removing the auxiliary thread used in weaving lace to secure the edges of two adjacent strips together during the weaving operation.

As is well known, in making lace on the circular lace machine one or more narrow strips of lace are made in a tube with the edges of the strips secured together by what is known as an auxiliary thread which is later pulled out to separate these strips of lace, and this auxiliary thread is usually in a different color from that of the thread of the lace so that it is easily distinguishable. In other types of lace machines the strips of lace may be woven flat, but adjacent strips are connected together by an auxiliary thread in the same manner. At the present time so far as known these auxiliary threads are removed by hand which is expensive, and also this operation is liable to injure the lace, as in removing by hand the threads are cut at suitable spaced points and then pulled out.

It is, therefore, an object of the present invention to provide a device which will effectively remove this auxiliary thread and will do it much more rapidly than can be done by hand, and will also do it without in any way injuring the lace.

In carrying out my invention I provide means for pulling out successively the short length of this auxiliary thread at its free end and moving it to one side away from the lace where this free end is cut off, and also provide means for continuously guiding and feeding the lace past the picking and cutting means so that the auxiliary thread is continuously pulled from the lace in short pieces and cut off, thus effectively removing the thread from the lace.

There are various ways in which this operation may be performed, but the preferred construction comprises an upright rotating element having a plurality of sets of teeth in its periphery and spaced from each other, which teeth as they rotate engage the auxiliary thread where it extends transversely between the edges of the lace and pulls a short length of the thread at its free end to one side and downwardly where these short lengths are cut off by means of blades carried on an element rotating in a plane extending transversely to the plane of the picking element. Means are provided for

continuously feeding the lace past the picking and cutting means, and a suction means is provided to remove the short pieces cut off. It is to be noted that one of the important features of my invention involves first pulling a short piece of auxiliary thread at its free end from the lace and to one side, and then cutting it off, so that the thread is not cut until it is removed from the lace.

With the foregoing and other objects in view, I have devised the construction illustrated in the accompanying drawings forming a part of this specification, similar reference characters being employed throughout the various figures to indicate corresponding elements. In these drawings,

Fig. 1 is a front elevation of a machine embodying the preferred form of device for carrying out my invention, certain parts being broken away to more clearly show the construction.

Fig. 2 is a top plan view thereof.

Fig. 3 is a rear end elevation looking from the left of Fig. 1.

Fig. 4 is a top plan view of the picking and cutting device on a somewhat enlarged scale with the guiding means for the lace removed.

Fig. 5 is a partial vertical section and partial side elevation thereof.

Fig. 6 is a vertical section taken at right angles to Fig. 5 substantially on line 6—6 of Fig. 4.

Fig. 7 is a vertical section substantially on line 7—7 of Fig. 4.

Fig. 8 is a horizontal section substantially on line 8—8 of Fig. 9 showing the oiling device for the rotating cutters.

Fig. 9 is a detailed vertical section of the oiling device, the cutter being shown in elevation.

Fig. 10 is a view similar to Fig. 5 showing the device removing a single auxiliary thread.

Fig. 11 is a view similar to Fig. 10 showing the device removing a single thread from a tubular piece of lace.

Fig. 12 is a top plan view thereof, and

Fig. 13 is a vertical section substantially on line 13—13 of Fig. 11.

The machine illustrated comprises a base or bed 15 on the top of which are upright supports 16 carrying a bed plate 17 and a top plate 18 spaced above the plate 17. 110

Mounted between these two plates in a suitable enclosed chamber 19 is the picker 20 and a cutter 21. The picker 20 is mounted on a horizontal shaft 22 so that it will rotate 5 in an upright plane and has a plurality of spaced arms 23 which carry one or more teeth 24 at their outer ends, and these teeth are inclined laterally so as to give a hook effect. The cutter 21 is mounted on an up- 10 right shaft 25 so that the cutter rotates in a plane transverse to the plane of rotation of the picker, and this cutter is provided with a plurality of spaced arms forming or carrying cutter blades 26. In the construction 15 shown the cutter has the same number of blades as the picker has arms 23, and they are mounted to overlap so that as the picker and cutter rotate the blades 26 pass through the spaces between the arms 23 and the arms 20 23 pass through the spaces between the cutter blades, this operation being secured through suitable gearing which will presently be described. Cooperating with the cutter blades 26 is a stationary blade 27 so 25 that the threads are cut with a shearing operation between the cutter blades and the stationary blade. The stationary blade is preferably mounted in a removable plate 28 mounted in an opening 29 in the top plate 30 18 leading to the chamber 19, this plate being secured in position by suitable screws 30. The plate 28 is provided on one side thereof with a notch 31 through which the picker rotates so that the picker is partly above 35 and partly below this plate and is rotated so that the teeth 24 pass down through this notch, and the stationary cutter blade 27 is mounted at one side of this notch with its cutting edge below the plate. Mounted above 40 this plate is the guiding means for the lace so that the lace will be placed in proper position relative to the picker. In the form shown in Figs. 1 to 6 the guiding means is arranged to present two auxiliary threads to 45 the picking and cutting means at the same time. The particular lace shown comprises two separate lace strips 32 with their edges connected together by means of the auxiliary threads 33 to form a tube, which is the 50 form in which the lace is woven. It is to be noted that the opposed edges 34 of the two strips are spaced a short distance apart and the auxiliary threads 33 pass back and forth over this space from one strip of lace to the 55 other, as indicated in Figs. 2 and 4. The guiding means for the lace comprises two members 35 having upwardly rounded portions 36 in which are star wheels 37 arranged with the points of the teeth projecting above 60 the tops of the guide members to engage the lace and prevent its sliding laterally, and to thus hold the space between the edges of the lace in proper alignment with the picker 20. After the lace passes over the rounded 65 portions 36 it is forced downwardly to a po-

sition where the auxiliary threads 33 can be engaged by the teeth 24. This downward movement is imparted by the guide member 38 secured to the cover 39 over the picker, and this cover also includes a guiding means 70 40 to separate the two pieces of the lace after they pass the picker, as shown in Fig. 2. A wire frame 41 is so located that the lace passes outside this frame and is kept properly spread out to keep the free edges 75 34 separated, as indicated in Figs. 4 and 6. The lace is drawn through this guiding means and past the picker by means of feeding rollers 42. These rollers are placed one above the other and preferably are provided with knurled surfaces so as to grip the lace. They are rotated by a suitable driving connection and are in driving connection with each other through the gears 43. The upper roll is mounted on a pivoted support 80 44, this support being pivoted by means of a pin 45 laterally at one side of the roll so that by swinging the support about this pivot the upper roll may be swung away from the lower roll to allow for insertion or 85 removal of the lace to or from between the rolls. The support carries a catch 46 pivoted to the support at 47, and has a hook 48 arranged to engage under a lug 49 to hold the upper roll elevated when swung away from the lower roll, a spring 50 tending to hold the hook in holding position. A handle 51 on the support is provided with a rod 52 slidably mounted therein and which may be depressed by means of a button 53 at its upper end to release the catch 46.

The operation of this portion of the device is as follows: the picker 20 and the cutter 21 are connected through suitable driving mechanism, which will later be described, so that they rotate in certain timing relation, an arm 23 and a blade 26 passing alternately by the stationary blade 27, so that the arms 23 pass through the spaces between the blades 26 and the blades 26 pass through the spaces between the arms 23. The lace is drawn through the guiding means 35, 38 and 41 by the rollers 42 and is held in proper position by these guiding means with the opposed free edges 34 of the strips of lace separated as indicated in Figs. 2 and 4, and as the lace is drawn forwardly the transverse portions of the auxiliary threads 33 are moved into the path of movement of the teeth 24 of the picker. These teeth engage these transverse portions as the picker rotates and pulls the portion of the auxiliary thread between the point of engagement and the free end of the thread downwardly through the notch 31 and in front of the stationary blade 27, as indicated in Fig. 6, the short free end of the auxiliary thread being indicated at 54, and it will be noted that this portion of the auxiliary thread is entirely removed from the lace. After it is 100 105 110 115 120 125 130

drawn to the position shown in Fig. 6 the next cutting blade 26 cuts this free end of the thread off as indicated in Fig. 6, the cutting operation being a shearing action between the stationary blade 27 and the movable blade 26. It will thus be apparent that the auxiliary thread is not cut until it has been drawn entirely clear from the lace. After this piece of thread has been cut the set of teeth on the next arm of the picker will engage another transverse portion of the thread and pull the short portion of the thread adjacent the last cut from the lace down through the notch 31 in front of the stationary blade 27, where it is cut off by the next movable blade 26, and so on, the operation being continuous. It will be understood that the thread is withdrawn from the lace by pulling downwardly a short length thereof adjacent the cut end and these short lengths are progressively cut off as soon as they are withdrawn from the lace. Thus the thread is positively and entirely removed from the lace and without in any way injuring the lace.

In order to remove these cut ends of the thread and prevent their passing back into the lace or into the mechanism, the chamber 19 in which the picker and cutter are mounted is connected by means of a pipe 55 to a suitable suction device, as a fan, which draws air through the chamber and carries the cut pieces of thread out to a suitable separating device.

The devices are driven from a shaft 56 which is driven by means of a suitable pulley 57 and a belt 58 from any suitable source of power. The pulley may include a hand wheel in order that the device may be turned over by hand in setting up or for any other reasons. The shaft 22 for the picker is driven from an upright shaft 59 through beveled gears 60 and the shaft 59 is driven from the shaft 56 by the beveled gears 61. The upright shaft 25 for the cutter is driven from the shaft 56 through the spiral gears 62. The feeding rolls are driven from the main shaft 56 through a worm 63 and the worm gear 64. This worm gear drives a spur gear 65 meshing with a gear 66 on a shaft 67 which shaft also carries the gears 68 and 69. An upright shaft 70 carries a gear 71 which is free to rotate on the shaft and also carries a collar 72 which is free to slide longitudinally on the shaft but is splined to the shaft by means of the key 73 so as to rotate therewith. This collar carries a gear 74 which may mesh with the gear 68, and also carries a gear 75 which may mesh with the gear 66. The lower end of the collar is provided with clutch teeth 76 which may mesh with clutch teeth 77 on the gear 71. The shaft 70 is connected to shaft 78 on which the lower roll 42 is mounted through the bevel gears 79. The gears

66, 68, 69, 71, 74 and 75 provide a change speed mechanism for driving the feeding rolls. If the clutch teeth 76 of the collar 72 engage the clutch teeth 77 of the gear 71, the rollers are driven through the gears 69 and 71. If the collar is shifted to bring either the gear 74 into mesh with the gear 68 or the gears 75 into mesh with the gear 66 the rolls are correspondingly driven from these gears, and as they are of different diameters the speed of the rolls may be varied through this mechanism. The collar 72 is shifted by means of the rack 80 (Fig. 1) engaging a gear 81 operated by a crank 82. By swinging this crank to the high or low or intermediate positions indicated the speed of rotation of the feed rollers and thus the rate of feed of the lace may be varied, as will be obvious. There is a clutch between the worm gear 64 and the shaft 83 carrying the gear 65 as shown in Fig. 1. The worm gear 64 is mounted on a sleeve 84 which is mounted to rotate in a bearing 85 in the base and carries the external clutch member 86. An internal clutch member 87 is mounted to slide on the shaft 83 and is splined to rotate therewith, and it may be shifted to and from engagement with the external clutch member 86 by means of a lever 88 and the fork 89. A spring 90 tends to hold the clutch in driving position.

An important portion of my device is a means for lubricating the cutter blades 26. In the present construction I have mounted on the under side of the plate 28, as shown in Figs. 6, 7 and 9, a fibre pad 91 held in any suitable holding means 92. The plate is provided with a passage 93 leading to the upper side of the pad from a nipple 94 which is connected to a tube 95 in turn connected to an oil cup, not shown. By this means oil is conducted from the cup to the pad 91 which is mounted immediately above the blades 26, and therefore, as these blades rotate they come in contact with the under side of the pad and are lubricated by the oil on the pad so that they do not become hot and unduly worn by coaction with the stationary blade 27.

In Fig. 10 I have shown a single thickness of lace passing through the device. This would be the arrangement where two flat pieces of lace are connected at one edge only, and it will be seen that the lace passes over the guiding members 35 and under the frame 41 and guide 38. The operation, however, is the same as in the first arrangement and in fact the guides are the same. In Figs. 11, 12 and 13, however, I have shown how a tube comprising a single strip of lace with its opposite edges connected by the auxiliary thread is passed through the device. In removing the auxiliary thread of this arrangement it will be obvious that the upper side of the lace must be kept away from the

picker. The tubular piece of lace is indicated at 96 and the opposite free edges of the strip forming this tubular piece of lace are indicated at 97 and connected by the 5 auxiliary thread 33. Mounted above the guiding member 98, which in this case carries a single star wheel 99, is a wire frame or guide 100. This frame is curved transversely as shown in Fig. 13 so that the 10 lower portion of the tube of lace including the free edges 97 and the auxiliary thread 33 is held down against the upper side of the guide member and in engagement with the star wheel, and also so that it passes 15 under the curved guide 38 by which the auxiliary thread is guided down into the path of movement of the teeth 24 on the picker 20. The upper portion of the lace tube, however, is lifted by the frame 100 and 20 passes over the top of the guide 40 and the cover 39, as indicated in Figs. 11 and 13. The separated free edges are spread laterally by the guide 40 as indicated in Fig. 12, and the lace passes through the feed rollers 25 42 spread out flat.

Having thus set forth the nature of my invention, what I claim is:

1. In a machine for removing an auxiliary 30 thread from lace, means for pulling out the free end of the thread and cutting off the said free end after it has been pulled out.

2. In combination, means for pulling out the free end of the auxiliary thread from a 35 strip of lace and cutting off the said free end after it has been pulled out, and means for guiding the strip past said means.

3. In a device of the character described, 40 a picker for engaging and pulling to one side the free end of the auxiliary thread in a strip of lace, a cutter, and means for operating the cutter in certain timing relation with the picker to cut off the free end of the thread after it has been withdrawn from the lace.

4. In a device of the character described, 45 a picker comprising a rotary element having teeth to engage the auxiliary thread of a strip of lace and withdraw the free ends of said thread from the strip, and a cutter for cutting off the free ends after they have been withdrawn from the lace.

5. In a device of the character described, 50 a picker comprising a rotary element having teeth to engage the auxiliary thread of a strip of lace and withdraw the free end of said thread from the strip, means for guiding and feeding the strip continuously past said picker, and means for cutting off the free ends of the thread after they are withdrawn from the lace.

6. In a device of the character described, 55 a picker comprising a rotary element having spaced teeth to engage the auxiliary thread in a strip of lace and withdraw the free ends of said thread from the strip, a cutter

comprising a member mounted to rotate in a plane at substantially right angles to the plane of rotation of the picker, said cutter having spaced blades, a stationary blade co-operating with the rotating blades, and 70 means for rotating the picker and cutter so that the blades will pass between the teeth of the picker.

7. In a device of the character described, 75 a picker comprising a rotary element having spaced teeth to engage the auxiliary thread in a strip of lace and withdraw the free ends of said thread from the strip, a cutter comprising a member mounted to rotate in a plane at substantially right angles to the plane of rotation of the picker, said cutter having spaced blades, a stationary blade co-operating with the rotating blades, and 80 means for continuously guiding and feeding the lace past said picker.

8. In a device of the character described, 85 means for pulling to one side the free ends of the auxiliary thread in a strip of lace, means for cutting off said free ends after they have been withdrawn from the lace 90 comprising a rotating member having cutting blades, a stationary blade cooperating with the rotating blades, and means for lubricating the surfaces of the moving blades which engages the stationary blade including an oil carrying pad in position to be engaged by the surface of the rotary blades as they are rotated.

9. In a device of the character described, 95 a picker comprising a member mounted to rotate in an upright plane and having spaced teeth to engage the auxiliary thread joining the free edges of strips of lace to withdraw the free ends of said thread from the lace, a cutter having blades mounted to 100 rotate in a horizontal plane to cut off the free ends of the thread after they have been withdrawn from the lace, means for guiding the lace to bring the auxiliary thread across the path of movement of said teeth 105 with the edges of the lace on opposite sides thereof, and means for advancing the lace past said picker.

10. In a device of the character described, 110 a plate, a rotary picker extending above and below the plate and provided with teeth to engage the auxiliary thread of a strip of lace and withdraw the free ends thereof from the lace, a cutter having blades mounted to rotate beneath the plate in a plane 115 transverse to the plane of the picker, a stationary blade arranged to cooperate with the movable blades to cut off the free ends of the thread after they have been withdrawn from the lace, means for guiding the lace in proper relation to the picker, and an oiling pad on the under side of the plate to engage the movable blades.

11. In a device of the character described, 120 a guiding means, a rotary picker associated 125

with the guiding means and provided with spaced sets of teeth to engage the auxiliary thread joining the edges of strips of lace in the guiding means to withdraw the free ends thereof from the lace, a cutter mounted to rotate beneath the guiding means in a plane transverse to the plane of the picker and having a plurality of spaced blades, the picker and cutter being arranged so that the 5 blades pass between the sets of teeth and the teeth between the blades, and a stationary blade cooperating with the movable blades to cut off the free ends of the thread after they have been withdrawn from the lace.

10 12. In a device of the character described, a picker comprising a member mounted to rotate in an upright plane and provided with teeth on its periphery to engage the auxiliary thread joining the free edges of 15 strips of lace to pull the free ends of the thread from the lace, a cutter having blades mounted to rotate in a plane transverse to

the plane of the picker, a stationary blade mounted to cooperate with the movable blades to cut off the free ends of the thread 25 after they have been withdrawn from the lace, guiding means to hold the lace in proper relation to the picker, and a suction means for carrying away the pieces of thread cut off.

30 13. In a device of the character described, a continuously operating picking means arranged to engage the free ends of the auxiliary thread joining the edges of strips of lace and to withdraw these ends from the lace, means for cutting off the free ends 35 after they have been withdrawn from the lace, guiding means to hold the lace in proper relation to the picker, feeding rolls to engage the lace and draw it through the 40 guiding means, and means for operating the rolls.

In testimony whereof I affix my signature.
GUSTAVE A. PIEPENBRING.
